CHAIN CONSTRUCTION

Corwin S. Jones, Tiffin, Ohio, assignor to Webster
Manufacturing, Inc., Tiffin, Ohio, a corporation
of Ohio

Application May 10, 1946, Serial No. 668,727

1 Claim. (Cl. 74—251)

1

This invention relates to improvements in chain construction, of the type embodying outside and inside bars forming the links, the bars of the links being laterally spaced, and which links are pivotally connected together by means of a thimble or bushing and a pivot pin.

It is well known, in the manufacture of chains of this character, that are constructed of cast material, the side bars and the bearing thimbles are cast all in one link.

In the manufacture of what is known as steel chains, the bushings or thimbles are milled at their ends and pressed into oblong holes punched in the inside bars of the links, both for the purpose of maintaining the thimbles or bushings against turning with respect to the bars, and to provide sufficient bearing area on the pin, to give the chain reasonable life. The pivot pin is generally milled at one end or provided with a lug to prevent its turning in the outside bars.

It is one of the objects of the present invention to provide an improved chain of this character in which the bearing thimble or bushing is constructed separately from the bars and then welded, brazed, or similarly secured to the inner face of one of the inner link bars.

A further object is to provide improved means for securing the thimble or bushing in position.

To the attainment of these ends and the accomplishment of other new and useful objects as will appear, the invention consists in the features of novelty in substantially the construction, combination and arrangement of the several parts, and in substantially the method of carrying the invention into operation, hereinafter more fully described and claimed, and shown in the accompanying drawing exemplifying this invention and in which

Fig. 1 is a top plan view of a chain of this character, constructed in accordance with the principles of this invention.

Fig. 2 is a side elevation of Fig. 1.

Fig. 3 is an enlarged detail sectional view of the thimble or sleeve, and one end of the inner link, showing the manner of attaching the thimble to the link.

Fig. 4 is a view similar to Fig. 3, showing the thimble attached to the link.

Fig. 5 is a top plan view, similar to Fig. 1, of another form of chain.

Referring to the drawing the numeral 10 designates the outside bars, and 11, the inside bars of a pair of links of a chain, and which bars may be of any desired or suitable size and of any desired configuration. The numeral 12, 55

2

designates a thimble or bushing which is constructed separately from and is disposed between the ends of the inside bars 11, and may be constructed of any suitable material, preferably steel. One end of the thimble is preferably shaped to provide a circumferential reduced portion or flange 13, or may be otherwise suitably prepared for projection welding. The welding may be accomplished in any suitable manner, such as by means of clamp type electrodes 14—15, to produce a welded joint 16, and by means of which joint the thimble will also be supported and held in position by one of its ends. The thimble is provided with a bearing opening 17, therethrough which registers with an opening 18 in the end of the inner bar, an opening being also provided in the end of the co-operating inner bar 11. The thimble is of a length that both of its ends will contact the respective inner bars 11, and may be provided with lubrication openings 19.

The openings 20, in the adjacent ends of the proximate outside bars, register with the openings 18, in the inside bars, and a pivot pin 21, passes through the registering openings. A head 22 is provided on one end of the pin, and the other end of the pin is fastened in any suitable manner, such as by being upset or deformed as at 23, or by means of a fastening element 24, such as a cotter pin or the like passing therethrough.

The bars 10—11 may be either straight or offset respectively as at 25.

While the preferred forms of the invention have been herein shown and described, it is to be understood that various changes may be made in the details of construction, and in the combination and arrangement of the several parts, and in the method of producing the invention, within the scope of the claim, without departing from the spirit of this invention.

What is claimed as new is:

A chain consisting of alternate wide and narrow links, each narrow link comprising two laterally spaced parallel side bars and two tubular thimbles bridging the gap between the side bars and serving as spacers therebetween and located individually near the respective ends of the narrow link, one end only of each thimble abutting and welded to the inner face only of one only of said side bars, the other thimble similarly abutting and welded at one end only to the inner face only of the other side bar, each of said side bars being apertured in registration with the bores of the two thimbles, each wide link comprising two laterally spaced parallel side bars the end por-

tions of which overlap the proximate end portions of the side bars of the adjacent narrow links, each side bar of each wide link having an aperture in registration with the aperture in the proximate end of the narrow-link side bar which it overlaps, and pivot pins, each of which extends through the bore of one of said thimbles and through the several registering apertures and serving to pivotally intercouple a narrow link with an adjoining wide link.
